(57) **CLAIM**

The ornamental design for a pallet truck pump housing, as shown and described.

DESCRIPTION

FIG. 1 is a perspective view of a pallet truck pump housing taken from the right rear showing our new design; FIG. 2 is a perspective view of the pump housing taken from the left rear thereof;

FIG. 3 is a top view of the pump housing of FIGS. 1 and 2; FIG. 4 is a bottom view of the pump housing of FIGS. 1 and 2;

FIG. 5 is an elevational view of the right side of the pump housing of FIGS. 1 and 2;

FIG. 6 is an elevational view of the left side of the pump housing of FIGS. 1 and 2;

FIG. 7 is an elevational back view of the pump housing of FIGS. 1 and 2;

FIG. 8 is an elevational front view of the pump housing of FIGS. 1 and 2;

FIG. 9 is a perspective view of the pump housing of FIGS. 1 and 2 taken from the front of a pallet truck on which the pump housing is installed; and,

FIG. 10 is a perspective side view of the pump housing of FIGS. 1 and 2 taken from the left side of a pallet truck on which the pump housing is installed.

The broken line showing of a pallet truck in FIGS. 9 and 10 is for illustrative purposes only and forms no part of the claimed design.

1 Claim, 3 Drawing Sheets
